UNITED STATES PATENT OFFICE.

CHARLES S. MCCOY, OF KANSAS CITY, MISSOURI.

RELEASING DEVICE FOR POULTRY-HOUSE DOORS.

1,203,026.

Specification of Letters Patent.

Patented Oct. 31, 1916.

Application filed January 18, 1916. Serial No. 72,701.

To all whom it may concern:

Be it known that I, CHARLES S. McCoy, a citizen of the United States, residing at Kansas City, in the county of Jackson and 5 State of Missouri, have invented certain new and useful Improvements in Releasing Devices for Poultry-House Doors, of which the following is a specification.

This invention relates to releasing devices 10 for poultry house doors and my object is to produce mechanism adapted for operation by a fowl.

Another object is to produce an attachment of the character mentioned which can 15 be manufactured and sold very cheaply.

With these objects in view the invention consists in certain novel and peculiar features of construction and organization as hereinafter described and claimed; and in 20 order that the invention may be fully understood reference is to be had to the accompanying drawing in which,

Figure 1, is an interior view of the front wall of a poultry house equipped with mechanism embodying my invention. Fig. 2, is a central vertical section taken on the line I—II of Fig. 1. Fig. 3, is a plan view of a part of a chicken house with the roof removed and with a certain part broken away 30 to expose parts otherwise hidden in said figure. Fig. 4, is a fragmentary elevation to show the device arranged for operation by a fowl, such as a duck.

In the said drawing, 1 indicates a poultry 35 house of any suitable type and provided preferably with a window 2 above the door opening 3. Secured preferably to the outer side of the house around the door opening is a rectangular frame 4 to which a door 5 is 40 hinged as at 6, the arrangement being such that when the door is opened it rests upon the ground as indicated by dotted lines in Fig. 2, and secured to the inner side of the door is a draw pull 7 forming a handle by 45 which the door may be conveniently closed from inside the house.

8 is a shaft extending through the front wall of the house vertically above the door and said shaft is journaled in a pair of 50 bearing brackets 9 and 10 respectively secured to the inner and outer sides of the well, and secured upon the outer end of the shaft is an arm or button 11 adapted when occupying a vertically pendent position as 55 shown in Fig. 2, to lock the door against opening movement, it being noted by refer-

ence to Figs. 2 and 3 that springs 12 interposed between the side portions of frame 4 and the door will tend to swing the door open the instant the door is unlocked by 60 the tripping of the arm or button.

In order to protect the outside of the operative parts from exposure to snow or sleet, a shield 13 is secured to the outer side of the house and overhangs the outer portion of the shaft and the door. 65

For the purpose of preventing the tripping of the door securing arm or button through pressure applied upon it by the paw or nose of an animal, a substantially 70 J-shaped guard 14 is pivotally suspended from the shield so that it will swing up against the door under the arm or button and thus protect the same from the animal. At the same time it will readily swing aside 75 to permit the door to open and can be readily swung outwardly out of the way to permit the door to be closed.

Referring now to the mechanism for holding the door in closed position and for rotating the shaft to opening position, 15 is a crank arm mounted on the inner end of the shaft and normally supported upon an angle bracket 16 secured to the front wall of the house. At the opposite side of the pivot 80 from said bracket the arm is pivotally connected by a link 17, to a lever 18 pivoted to an angle bracket 19, which is pivotally suspended from a bracket 20 secured to a fixed point of the poultry house. At its opposite end the lever is loosely hinged at 21 to a lever 22 hinged at 23 to another fixed point on the poultry house. The link 17 is connected to lever 18 adjacent the window by preference. The lever members 18 and 95 22 constitute a jointed lever so that one member thereof can move endwise as the lever swings downward and thus impart direct endwise pressure through the link onto the crank arm 15. 100

The parts will be so proportioned and balanced that a fowl weighing about a pound and a half, when standing upon either of the levers adjacent the window will overcome the weight of the crank arm 105 15 and the locking arm or button and the friction between the latter and the spring pressed door, and swing said arms to the positions shown by dotted lines in Fig. 1, the jointed ends of the levers of course assuming substantially the position shown by dotted lines in the same figure. As this 110

disposition of parts is effected, the door opens and remains in such position until some one closes it.

As well known poultry will seek the light and knowing this I found that by locating the device relatively to the window as shown, a fowl will invariably fly up toward the light and alight upon one of the levers. Any fowl alighting upon either of the levers at one side of the window will also walk down upon it toward the window and by the time a position is attained directly opposite the window will apply sufficient weight to effect the unlocking of the door as explained.

I have found that after the device has been in use for a day or two the window can be covered and the fowls will still fly up and light upon the levers and effect the opening of the door.

For use in a house for ducks and geese which cannot fly up to levers 18 and 22, link 17 is disposed in a pendent position and lever 18 without the brackets 19, is arranged in a slightly inclined position with one end resting upon the ground. The ducks or geese quickly learn that by stepping on this inclined lever the opening of the door is effected and thus in a short time can be relied upon to let themselves out of the poultry house.

The mechanism properly proportioned and preferably arranged as in Fig. 1, can be used in pigeon lofts and the pigeons soon learn that by alighting on the levers 18 and 22, the door will be opened to permit them to leave the loft.

After the door is opened the crank arm 15 being relieved of the weight of the fowl or fowls returns the parts to the position shown by full lines Fig. 1 and when it is desired to close the door the operator will raise arm 15 and hold it elevated until he closes the door. The release of the arm will then result in its return to the position shown by full lines in Fig. 1. The device is then in position for operation in the morning by the fowl.

From the above description it will be apparent that I have produced door opening attachments embodying the features of advantage enumerated as desirable in the statement of the object of the invention and which are susceptible of modification in minor particulars without departing from the principle and scope of the appended claims.

I claim:

1. The combination with a poultry house having a door opening, a door for automatically opening when not fastened in closed position, a rock shaft, an arm secured

to the shaft and engaging the door to hold the same closed, means for yieldingly holding the rock shaft with the said arm in locking position, means for operation when weighted as when a fowl is supported upon it, a connection for transmitting power from the fowl-operated means to the holding means to overcome the resistance of the latter and thereby rock the shaft until the locking arm is tripped from engagement with the door, a shield or guard covering the free edge of the door, the locking arm and the part of the shaft at the outer side of the house, and an extension pivotally suspended from the guard and adapted to prevent access to the locking arm and free to be swung aside by the door in the opening movement of the same.

2. The combination with a poultry house having a door opening, a door for automatically opening when not fastened in closed position, a rock shaft extending through the wall of the house above the door opening, a locking arm secured to the outer end of said shaft and a weighted arm secured to the inner end of said shaft and holding the locking arm overlapping the door at its outer side when the door is closed, means for supporting the weighted arm against accidental movement tending to swing the locking arm past locking position, a lever for actuation by a fowl when perched upon it, and means for transmitting power from said lever to said weighted arm to effect rotation of the shaft and withdrawal of the locking arm from the path of opening movement of the door.

3. The combination with a poultry house having a door opening, a door for automatically uncovering said opening when unfastened, a rock shaft, a locking arm secured to the rock shaft and engaging the door to hold the same closed, a weighted arm secured to the rock shaft within the house to hold the locking arm in locking position, a jointed lever within the poultry house and hinged at one end to a fixed point on the latter, a bracket pivoted to the opposite end of the jointed lever and pivotally suspended from a fixed point within the poultry house to permit the connected lever member to move endwise when it swings, and a link pivotally connecting the jointed lever with the weighted arm to transmit power from the former to the latter to effect rotation of the rock shaft.

In testimony whereof, I affix my signature, in the presence of two witnesses.

CHARLES S. McCOY.
